PROCESS AND COMPOSITIONS FOR STABILIZING
THE THERMAL GENERATION OF PESTICIDAL
FOGSJohn F. Brandenburg, Lombard, Ill., and Paul G. Gordon, Hammond, Ind., assignors to Standard Oil Company, Chicago, Ill., a corporation of Indiana
No Drawing. Filed Feb. 28, 1955, Ser. No. 491,201
10 Claims. (Cl. 167—39)

Our invention relates to improvements in the control of pests and insects by means of pesticidal fogs generated by thermal means. More particularly it provides an improved process for preventing carbon deposition in fog generated equipment and provides stabilized pesticidal compositions for generation of fogs.

Oil carried insecticidal compositions are widely used in thermal fog generating machines for the control of insects, particularly flies and mosquitos. Typically, thermal fog generators depend upon a blast of air, heated to about 1000° F. in a combustion chamber, to break up the insecticide particles into aerosol type fogs. For example, in the TIFA insecticidal fog applicator (made by Todd Shipyards Corporation), one of the most widely used generators of the thermal aerosol type, air is pumped to a combustion chamber where it is raised to a temperature of about 950° to 1050° F. The hot gas stream is pumped, at a pressure of about 40 to about 70 pounds p.s.i.g., to an atomizer cup. The liquid to be fogged is introduced to the atomizer cup at lower pressure, e.g. about 25 p.s.i.g., and is atomized into a fine spray. The spray is dispersed as a fog by expansion through a nozzle.

Despite the extremely short residence time in the atomizer cup and fogging nozzle, the severe high temperature conditions result in very rapid carbon formation. It is often necessary to clean out the atomizer cup and nozzle every few hours under continuous operating conditions. The resulting down-time is a major cost factor in fogging operations since complete dismantling of the nozzle assembly is necessary for cleaning. This is troublesome on the job location because fogging operations are normally conducted in the very early morning (5 a.m. to 8 a.m.) or the late evening (7 p.m. to midnight) when it is usually dark and because fogging operations are usually conducted in locations remote from maintenance facilities. Moreover, after about an hour of fogging before complete stoppage, carbon deposition interferes with fogging efficiency to an extent creating a serious problem in the field.

Experiments have been made varying the oil carrier for the insecticidal solution or emulsion in an effort to reduce carbon deposition. Although the use of highly refined light oils such as kerosenes in place of the usual heater and furnace oils has effected some improvement, the basic problem remains because of the inherent instability of most oils and other organic components of the fogging compositions under the extreme conditions of temperature and pressure change encountered in thermal fogging operations. We have found, however, that carbon formation in the generation of pesticidal fogs can be substantially eliminated by including a stabilizer in the material to be fogged. The stabilizer of our invention is a detergent-dispersant of the type commonly employed in motor oils. This is a preferentially oil soluble metal soap of a structure including a strongly polar group coupling the metal with a high molecular weight hydrocarbon group, preferably containing a long chain. The most suitable detergent-dispersant known to us for use as a fogging stabilizer is a metal soap of a phosphorus-sulfurized reaction product of a hydrocarbon of sufficient

2

molecular weight to impart preferential oil solubility to the detergent structure. For example, a potassium or barium neutralized reaction product of phosphorus sulfide and an olefin polymer, advantageously a polybutene fraction of about 450 to 500 molecular weight, has special value. Materials of this sort are described in U.S. Patents 2,316,080, 2,316,082 and 2,377,955. We have found that combination of a detergent of this type with a polyamine such as a long chain, N-alkyl propylene diamine or organic salt thereof has special advantage in providing long continuous periods of fogging operation free from shutdown caused by carbon deposition and nozzle clogging.

In the practice of the invention, the stabilizer is usually incorporated in the pesticidal or insecticidal composition which is to be fogged. In general, the insecticidal composition is formulated as a concentrate of the selected insecticide, e.g. DDT, in an oil carrier for economy in shipping and handling. Before fogging, the concentrate is cut-back with oil to the specified insecticidal concentration, e.g. about 5 to 8 percent for DDT. The concentration of insecticide must be selected in accordance with the level of effective concentration of the particular insecticide for the particular pest or insect to be controlled. The stabilizer of the invention is usually made up in the form of an oil concentrate, for example, a concentrate containing 10 to 50 percent of the oil-free, active components in a light cycle oil, boiling in the range of 450 to 750° F., of the type derived from petroleum cracking operations. The stabilizer concentrate then can be added to the insecticidal concentrate or to the cut-back oil. Alternatively, the stabilizing components can be incorporated with the insecticide in the original formulation.

To illustrate specific application of the invention, a fogging composition which had been giving the difficulties characteristic of conventional oil-carried insecticidal solutions and emulsions was modified by use of a stabilizing additive of the invention. The original formulation was an emulsifiable concentrate containing 25 percent DDT in an aromatic solvent comprising alkyl naphthalenes boiling in the range 278° to 410° F. (Indocene 70). The formulation also included 3 percent Triton X-100, an alkylated aryl polyethylene oxide condensation product, as an emulsifying agent and 1.5 percent calcium mahogany soap, an oil soluble petroleum sulfonate. This composition was cut back to 5 percent DDT with a furnace oil comprising a mixture of 60 percent virgin gas oil distillate and 40 percent catalytic cycle oil boiling in the range 300° to 650° F. and which contained 0.01 percent of an additive mixture comprising 0.004 percent of N-tallow propylene diamine (Duomeen T), 0.001 percent of N-tallow propylene diamine oleate and 0.005 percent of a potassium neutralized reaction product of phosphorus pentasulfide and butene polymer.

The stabilized composition was tested for the control of mosquitos and flies by fogging with a TIFA insecticidal fogging generator in operations extending over an entire summer. The operator of the test equipment reported that using on the average of 500 gallons per week not one minute of down time was required for cleaning. Two units were operated during the period without taking the nozzle assembly apart for cleaning. By contrast, the same operator had found that he was fortunate to fog over 3 to 5 hours, without completely dismantling the nozzle assembly for cleaning, using either ordinary No. 3 furnace oil or range oil. Thus, the major cause of lost time in conducting thermal fogging operations was eliminated while 100 percent efficiency at the fogging nozzle was assured.

In greater detail, the detergent-dispersant of the invention may be obtained by reacting a phosphorus sulfide with a hydrocarbon at a temperature of from about 200°

F. to about 600° F., and preferably from about 250° F. to about 500° F., using from about 1 percent to about 50 percent, and preferably from about 5 percent to about 25 percent by weight, of the phosphorus sulfide in the reaction. It is advantageous to maintain a non-oxidizing atmosphere, such as for example, an atmosphere of nitrogen above the reaction mixture. Usually, it is preferable to use an amount of the phosphorus sulfide that will completely react with the hydrocarbon so that no further purification becomes necessary; however, an excess of phosphorus sulfide can be used and separated from the product by filtration or by dilution with a solvent, such as hexane, filtering and subsequently removing the solvent by suitable means, such as by distillation. The phosphorus sulfide-hydrocarbon reaction products contain both sulfur and phosphorus. The reaction may if desired be carried out in the presence of an additional sulfurizing agent or the phosphorus sulfide-hydrocarbon reaction product can be sulfurized, as described in U.S. 2,316,087 issued April 6, 1943, to James W. Gaynor and Clarence M. Loane.

The hydrocarbon constituent of the reaction is preferably a mono-olefin hydrocarbon polymer resulting from the polymerization of low molecular weight mono-olefinic hydrocarbons or isomono-olefinic hydrocarbons, such as propylene, butylenes, and amylenes or the copolymers obtained by the polymerization of hydrocarbon mixtures containing isomono-olefins and mono-olefins or mixtures of olefins in the presence of a catalyst, such as sulfuric acid, phosphoric acid, boron fluoride, aluminum chloride or other similar halide catalysts of the Friedel-Crafts type.

The polymers employed are preferably mono-olefin polymers or mixtures of mono-olefin polymers and isomono-olefin polymers having molecular weights ranging from about 150 to about 50,000 or more, and preferably from about 300 to about 10,000. Such polymers can be obtained, for example, by the polymerization in the liquid phase of a hydrocarbon mixture containing mono-olefins and isomono-olefins such as butylene and isobutylene at a temperature of from about -80° F. to about 100° F. in the presence of a metal halide catalyst of the Friedel-Crafts types such as, for example, boron fluoride, aluminum chloride, and the like. In the preparation of these polymers there may be employed, for example, a hydrocarbon mixture containing isobutylene, butylenes and butanes recovered from petroleum gases, especially those gases produced in the cracking of petroleum oils in the manufacture of gasoline. U.S. 2,407,873 to Evering et al. describes a particularly suitable technique for polymerizing such olefins in the presence of an aluminum-chloride-hydrocarbon complex catalyst.

Essentially paraffinic hydrocarbons such as bright stock residuums, lubricating oil distillates, petrolatums or paraffin waxes may be used. The condensation products of any of the foregoing hydrocarbons or their halogen derivatives, with aromatic hydrocarbons can also be employed.

Examples of high molecular weight olefinic hydrocarbons which can be employed as reactants are cetene (C_{16}), cerotene (C_{26}), meline (C_{30}), and mixed high molecular weight alkenes obtained by cracking petroleum oils. Other olefins suitable for the preparation of the herein described phosphorus sulfide reaction products are olefins having at least 20 carbon atoms in the molecule of which from about 12 carbon atoms to about 18 carbon atoms, and preferably at least 15 carbon atoms, are in a long chain. Such olefins can be obtained by the dehydrogenation of paraffins, such as by the cracking of paraffin waxes, or by the dehalogenation of alkyl halides, preferably long chain alkyl halides, particularly halogenated paraffin waxes. Also, olefins derived from the synthol of hydrocarbon syntheses process may be employed. These are essentially straight chain compounds varying widely in molecular weight.

Also contemplated within the scope of the present in-

vention are the reaction products of a phosphorus sulfide with aromatic hydrocarbons such as benzene, naphthalene, anthracene, toluene, diphenyl, etc. and alkylated aromatic hydrocarbons such as, for example, an alkyl benzene characterized by having at least one alkyl group of at least four carbon atoms, and preferably at least eight carbon atoms such as a long chain paraffin wax.

The phosphorus sulfide reactant can be any phosphorus sulfide, such as for example, P_2S_3 , P_4S_3 , and preferably P_2S_5 .

The phosphorus sulfide-hydrocarbon reaction product normally shows a titratable acidity which is neutralized by treatment with a basic reagent. The phosphorus-sulfide-hydrocarbon reaction product when neutralized with a basic reagent containing a metal constituent is characterized by the presence or retention of the metal constituent of the basic reagent. Other metal constituents such as a heavy metal constituent can be introduced into the neutralized product by reacting the same with a salt 20 of the desired heavy metal.

The term "neutralized phosphorus sulfide-hydrocarbon reaction product" as used herein means a phosphorus sulfide hydrocarbon reaction product having at least about 1 percent of its titratable acidity neutralized by the reaction with a basic reagent and includes the neutralized phosphorus sulfide-hydrocarbon reaction products containing a metal constituent resulting from said neutralization or resulting from the double decomposition of the phosphorus sulfide-hydrocarbon reaction product treated 30 with a heavy metal salt.

The neutralized phosphorus sulfide-hydrocarbon reaction product can be obtained by treating the reaction product with a suitable basic compound such as a hydroxide, carbonate, sulfide, or an oxide of an alkaline 35 earth metal, e.g. calcium or barium, and preferably the latter, or an alkali metal such as, for example, potassium hydroxide or sodium hydroxide. The products are neutralized by mixing a suitable base (e.g. a 50 percent solution of KOH) therewith and heating to a temperature 40 in the range of from about 200° to about 400° F. After the base and phosphorus sulfide-hydrocarbon reaction product are mixed they are preferably steamed at a temperature of about 400° F. for about a half hour. The steaming may take place during neutralization.

The useful detergents appear to be characterized in composition and structure by the presence of a metal, e.g. potassium, calcium, barium, magnesium, zinc, aluminum etc., coupled to an oil solubilizing group by the polar phosphorus and sulfur containing group.

The polyamine constituents, which are employed in a preferred by more specific aspect of the invention, are amines such as N-n-cetyl-propylene diamine, the various "Duomeens" (products of Armour Chemical Division) which have the general formula $RNH_2CH_2CH_2NH_2$, 55 wherein R may be derived from coconut fatty acid ("Duomeen C"), from tallow fatty acid ("Duomeen T"), from lauric acid ("Duomeen 12"), or from soya fatty acid ("Duomeen S"), etc. The "Duomeens" are industrial or technical grade chemicals with an amine content of approximately 80% calculated as di-amine. The approximate melting ranges for each of the aforementioned "Duomeens" are: "Duomeen C"—20° to 24° C., "Duomeen 12"—28° to 32° C., "Duomeen S"—38° to 42° C., and "Duomeen T"—44° to 48° C.

The salts of the polyamines which also may be employed in accordance herewith may be prepared by reacting, under carefully controlled, non-dehydrating conditions, i.e. below about 200° F. and preferably below about 195° F., a carboxylic acid containing from about 6 to 70 about 20 carbon atoms, and preferably at least about 12 carbon atoms, e.g. hexanoic, nonanoic, lauric, stearic, oleic, linoleic, linolenic, palmitic, etc., with any of the described amines to obtain either the mono- or di-substituted acid salts of the amines. Care must be taken in

the preparation of such salts inasmuch as prolonged exposure to temperatures higher than about 200° F. results in the formation of amides or even glyoxalidines (if 1,2-substituted polyamines are employed) upon splitting out water. Among the very economical, commercially available salts of this type are the oleic acid mono- and/or di-salts of the Duomeens (above described), particularly of Duomeen T.

The stabilizers of the invention may be employed in variable proportions depending upon other components of the fogging composition. As little as 0.005 percent to as much as about 10 percent by weight may be desired. When the combination of detergent and amine are employed, about equal proportions are most suitable, but the amine may comprise as much as about 90 percent of the combination.

Insecticidal compositions containing the stabilizers of the invention may vary widely in composition because there are many pesticides and insecticides which are appropriately applied in this manner in large scale, insect and pest control operations. The compositions all employ an oil carrier for the insecticide although the oil concentrate can be cut-back with water to form an emulsion for fogging purposes. For this purpose an emulsifying agent such as an alkyl aryl sulfonate, a polyglycol ester, a polyoxyethylene derivative, and the like should be used. The oil carrier and/or the cut-back solvent may be a light hydrocarbon distillate, advantageously as produced in petroleum distillation or petroleum cracking operations. Usually a distillate of reasonably close cut distillate is desired having a flash point above the gasoline range for safety. Thus, naphthas, kerosenes and gas oils boiling in the range of about 300° to 550° or 650° F., are suitable. Depending upon the insecticide, special solvents such as xylene rich or solvents or chlorinated solvents may be required or desirable. A number of typical formulations are set out below.

Example I

	Percent
DDT	40
Emulsifying agent	25
Aromatic solvent	5
Potassium salt of P_2S_5 -polybutene reaction product	69.7
Duomeen T	0.015
Duomeen T-oleate	45

Example II

	Percent
DDT	25
Emulsifying agent	5
Aromatic solvent	69.985
Potassium salt of P_2S_5 -polybutene reaction product	0.015

Example III

	Percent
Toxaphene	60.0
Emulsifying agent	7.0
Mineral oil	32.0
Potassium salt of P_2S_5 -polybutene reaction product	0.5
Duomeen T	0.4
Duomeen T-oleate	0.1

Example IV

	Percent
Toxaphene	60.0
Emulsifying agent	7.0
Mineral oil	32.95
Potassium salt of P_2S_5 -polybutene reaction product	0.05

Example V

	Percent
Lindane	25.0
Emulsifying Agent	5.0
Aromatic solvent	69.835
Potassium salt of P_2S_5 -polybutene reaction product	0.5
Duomeen T	0.4
Duomeen T-oleate	0.1

Example VI

Malathion	50.0
Emulsifying Agent	6.0
Aromatic solvent	43.67
Potassium salt of P_2S_5 -polybutene reaction product	.33

In the above examples, the mineral oil may be a kerosene or light gas oil, and the aromatic solvent may be with advantage an aromatic solvent of the mixed alkyl benzenes or mixed alkyl naphthalenes types recoverable from catalytic hydroformates.

We claim:

1. In a process for control of insects and pests by generating pesticidal fogs from a fogging liquid comprising an oil-carried pesticidal composition by means of equipment for atomization of the fogging liquid at high temperature, the improvement which comprises using, as a stabilizer, an oil soluble metal soap of a phosphorus sulfide-high molecular weight hydrocarbon reaction product in said fogging liquid in an amount effective to reduce formation of coke by thermal decomposition of the pesticide composition.

2. The process of claim 1 in which the stabilizer also contains an N-substituted alkyl propylene diamine in which the alkyl group contains from about 6 to about 30 carbon atoms.

3. The process of claim 1 in which the stabilizer is a potassium soap of a phosphorus pentasulfide-polybutene reaction product.

4. A stabilized composition for thermal generation of pesticidal fog which comprises an oil carrier, an oil soluble pesticide suitable for fogging in an oil carrier medium and a stabilizer comprising a metal salt of a phosphorus sulfide-high molecular weight hydrocarbon reaction product in an amount effective to reduce carbon deposition thereof in thermal aerosol equipment.

5. The composition of claim 4 in which the stabilizer is a metal salt of a phosphorus pentasulfide-polybutene reaction product.

6. The composition of claim 5 in which the stabilizer is a potassium salt of a phosphorus pentasulfide-polybutene reaction product.

7. The composition of claim 5 in which the stabilizer is a barium salt of a phosphorus pentasulfide-polybutene reaction product.

8. The composition of claim 4 in which the stabilizer includes an N-alkyl propylene diamine containing from about 6 to about 30 carbon atoms in the alkyl group.

9. The composition of claim 8 in which the amine is N-tallow propylene diamine.

10. The composition of claim 8 in which the stabilizer mixture includes an oleic acid salt of the propylene diamine.
